UNITED STATES PATENT OFFICE.

FRANK N. KELSEY, OF NEW HAVEN, ASSIGNOR OF PART INTEREST TO
JOSEPH C. PECK, OF SAME PLACE, AND JAMES GRAHAM, OF ORANGE,
CONNECTICUT.

SWITCH-SIGNAL.

SPECIFICATION forming part of Letters Patent No. 399,538, dated March 12, 1889.

Application filed March 17, 1888. Serial No. 267,456. (No model.)

To all whom it may concern:

Be it known that I, FRANK N. KELSEY, a citizen of the United States, residing at New Haven, in the State of Connecticut, have invented new and useful Improvements in Railway Signaling Apparatus, of which the following is a specification.

My invention relates to that class of railway-signals which elevate a semaphore-arm to indicate "danger" when a draw-bridge or switch to which a part of the mechanism is connected is in such a position that an approaching train is in danger of leaving the track.

My invention has for its object to provide a means of raising and lowering a semaphore-arm by the same mechanism which unlocks the draw-bridge or opens the switch, and also to provide for the expansion and contraction of the wire connecting the mechanism at the draw-bridge or switch with the semaphore-arm.

In the accompanying drawings, Figure 1 is a plan view of my improved railway signaling apparatus: Fig. 2 is a side view of the same. Fig. 3 is an end view of the mechanism which is situated at the draw-bridge. Fig. 4 is an end view of the mechanism at the semaphore-post, and Fig. 5 shows the pawl in engagement and released.

Referring to the drawings, A denotes the operating-lever fastened to the shaft a and connected at its lower end to a bolt, B, by means of a pin. The bolt B slides in suitable guides fastened to the floor. Pivoted on the lever A is the dog d, which is caught and held by the projection e on the frame C, when the lever is moved to the position indicated by the dotted lines in Fig. 2, thus preventing backward motion of the lever until the dog is raised by the latch-lever f, pivoted near the upper end of the lever and connected to the dog by a suitable rod. A sprocket-wheel, D, is pivoted loosely on the same fulcrum as the lever A. A ratchet, g, is formed on the side of the sprocket-wheel nearest to the lever and adapted to be engaged by a pawl, h, pivoted on the lever A, which pawl has a weighted end, r, opposite to the end engaging with the

ratchet. When the draw-bridge is locked and the lever is in the position shown in Fig. 2, the weighted end of the pawl bears against the stop i, and is thus thrown out of engagement with the ratchet, and the sprocket-wheel is then free to be turned by the expansion or contraction of the chain l leading to the semaphore. A bolt-lock, E, swings at right angles to and across the line of motion of the bolt on a pin fastened beside the bolt and separate from it. This lock has an outwardly-projecting end adapted to be engaged and lifted by a wedge-shaped rib, k, on the socket F, fastened to the draw-bridge, to receive the end of the bolt, and when the bolt-lock is thus raised the bolt may be moved outward by the operating-lever to lock the draw-bridge. This chain passes partially round the wheel D, over a suitable guide-pulley, and is connected at the end to a weight, G, which keeps the chain taut at all times when the pawl is not in engagement with the ratchet, thus taking up expansion and allowing for contraction. The chain extends from the wheel D, along the side of the track over suitable guide-pulleys, to the underside of a pulley at the foot of the semaphore-post. It then passes vertically upward and over a pulley, m, which turns on a bearing fastened to the post above the semaphore-operating lever. The chain passes downward from the pulley and is connected at its end to the lever H. The lever H turns at one end on a fulcrum, s, which is secured to the post. This lever passes through a fork, n, formed on the lower end of the rod I, which is connected at its upper end to the semaphore-arm K by means of a bolt passing through a slot, o, in the rod and into the arm. The function of this slot is to relieve the rod and semaphore-arm from the shock due to the momentum of the parts when in motion. On the rod I counter-weights p are placed to overbalance the weight of the blade of the semaphore-arm so that the arm will be raised to the position shown by the dotted lines in Fig. 4, when the lever H is permitted to descend by the chain becoming slack.

A bearing, l, is secured near the outer side

of one of the rails of the track, in which is fulcrumed the lever M. One end of this lever extends from the bearing nearly to the side of the rail, with its upper surface slightly above the top of the rail, and the other end of the lever extends from the bearing to the semaphore-post into a slot, t, which limits its downward motion. Connected with it near the post is the rod q, which passes upward and has its upper end bent at right angles to the length of the rod.

An ordinary gong, X, is fastened to the post in such a position as to be struck by the hammer P. The hammer is pivoted on the post above the lever H at right angles to and across the path of its travel. The hammer-fulerum is so located that when the lever is drawn up by the chain the bell-hammer is lifted and held in contact with the side of the gong. This bell-hammer has an end projecting on the opposite side of the fulerum from the end which strikes the gong and passing under the hooked end of the rod q. This rod is of such a length that when the hammer is lifted by the lever H the wheels of a train strike the end of the lever M, thereby producing vertical motion of the opposite end of the lever, and the rod q will not permit the bent upper end to come into contact with the hammer before its motion is checked by the slot t, and yet allows it to act freely on the bell-hammer when the lever is down.

The operation of my improved railway signaling apparatus is as follows: Supposing the draw to be locked, as shown in the drawings, the pawl h will then be held out of engagement with the ratchet g by the stop i. The weight G being heavier than the parts operated by the chain l, raises the lever H, and as the rod I rests on the lever it is thereby also raised and the semaphore-arm permitted to drop to the position indicating "safety," in consequence of the blade of the arm being heavier than that part of the arm on the opposite side of its fulerum. The bell-hammer is also raised by the lever H, and thereby held out of contact with the bent end of the rod q. To unlock the draw, the operator pushes the lever A over, thereby throwing the bolt B out of the socket F. The pawl h, being carried on the lever A, moves with it away from the stop i, and as the end r is heavier than the opposite end the pawl is brought into engagement with the ratchet g, thereby connecting the sprocket-wheel D to the lever A, and then the motion of the lever in withdrawing the bolt B lifts the weight G. When the weight G is lifted, the chain l becomes slack, and the lever H, to which it is connected at the semaphore-post, being weighted at its outer end, drops to the position shown by the dotted lines in Fig. 4. The rod I, being weighted, descends with the lever and thereby brings the semaphore-arm to the position indicating "danger." The heavier end of the bell-hammer P, resting upon the lever H, descends

with it, thus bringing the lighter end into contact with the bent end of the rod q. As one end of the lever M projects above the top of the rail, the wheels of a passing train strike and depress it, thereby raising the opposite end, to which is connected the rod q, having a bent end in contact with the bell-hammer. When the wheel has passed off from the short end of the lever, the long end will fall, carrying with it the rod q, and thereby causing the hammer to strike the gong. This operation is repeated as each wheel passes over the short end of the lever L. By ringing the gong the attention of the engineer is called to the fact that the semaphore-arm indicates "danger."

It is evident that should the chain l break the semaphore-arm will rise to the position indicating "danger."

I claim as new and desire to secure by Letters Patent—

1. In railway signaling apparatus, the combination, with the operating-lever and the bolt operated thereby, of a bolt-lock pivoted beside the bolt and adapted to drop across the end of the bolt at right angles to its line of motion when the bolt is fully retracted and prevent forward motion of the bolt, substantially as shown and described.

2. The combination of an operating-lever with the bolt B, operated thereby, to lock the draw-bridge or switch, the bolt-lock E, pivoted beside the bolt and adapted to drop across the end of the bolt, the dog d, pivoted to the lever on the side of the lever-fulerum, opposite to the pawl h, and adapted to be caught and held by the projection e on the frame, a sprocket or chain wheel provided with a ratchet, g, formed on its side, the pawl h, pivoted on the lever adapted to engage at one end with the ratchet, and having its opposite end weighted and so shaped as to come in contact with a stop, and thereby be thrown out of engagement with the ratchet when the operating-lever is at one end of its travel, and a chain passing around the chain-wheel, connected at one end to a weight and at the other end to the mechanism for operating the semaphore, substantially as described.

3. In combination, the weighted lever H, pivoted at one end and adapted to be lifted and held up by a chain, l, the rod I, having at its lower end a fork which engages and rests upon the lever, and provided at its upper end with a slot, and a semaphore-arm connected to the rod I by a bolt passing through the slot in the rod and into the arm near its fulerum, substantially as and for the purpose specified.

4. In railway signaling apparatus, the combination, with a bell or gong and suitable mechanism for operating it fixed beside the rails of the track, of the lever H, the rod I, provided with a forked end, n, and a slot, o, in the other end, the semaphore-arm K, the chain or wire l, the chain-wheel D, with a ratchet, g, formed on the side of it, the pawl

h, the lever *A*, the dog *d*, pivoted on the lever, and the stops *i* and *e*, all combined as and for the purpose specified.

5. In combination, the operating lever *A*, the dog *d*, pivoted on the lever, the sprocket or chain wheel *D*, with a ratchet, *g*, formed on the side of it, the pawl *h*, pivoted on the lever *A* and provided with a weighted end, the stop *i* on the frame, the bolt *B*, the bolt-lock *E*, the socket *F*, carrying the rib *k*, the weight *G*, the chain or wire *l*, the lever *H*, the

rod *I*, provided with a forked end, *n*, and a slot, *o*, in the other end, the semaphore-arm *K*, the lever *M*, the rod *q*, the bell-hammer *P*, and the bell or gong *N*, all combined substantially in the manner and for the purpose specified. 15
